United States Patent [19]

Zernell

[11] Patent Number: Des. 300,907

[45] Date of Patent: ** May 2, 1989

[54] SURFACE TEMPERATURE LOSS
MEASURING DEVICE

[75] Inventor: Stig R. Zernell, Saltsjöbaden,
Sweden

[73] Assignee: Svenska Matapparater F.A.B., Farsta,
Sweden

[**] Term: 14 Years

[21] Appl. No.: 850,908

[22] Filed: Apr. 8, 1986

[30] Foreign Application Priority Data

Oct. 8, 1985 [SE] Sweden 85-2412

[57] CLAIM

The ornamental design for a surface temperature loss measuring device, as shown and described.

DESCRIPTION

FIG. 1 is a front and bottom-left perspective view of a surface temperature loss measuring device showing my new design;

FIG. 2 is a rear and top-right perspective view thereof;

FIG. 3 is a front and top right perspective view thereof with the detector in an alternative position;

FIG. 4 is a rear and bottom-left perspective view of FIG. 3.

FIG. 1

FIG. 2

FIG. 3

FIG. 4
